UNITED STATES PATENT OFFICE

117,036

DESIGN FOR A STREET SIGN

Anna M. Elliot, Dallas, Tex.

Application May 25, 1938, Serial No. 77,362

Term of patent 3½ years

To all whom it may concern:

Be it known that I, Anna M. Elliot, a citizen of the United States, residing at Dallas, in the county of Dallas and State of Texas, have invented a new, original, and ornamental Design for Street Signs, of which the following is a specification, reference being had to the accompanying drawing, forming part thereof.

The figure is a perspective view of a street sign, showing my new design, a portion of the support being indicated in broken lines.

The letters and numerals shown on the drawing are illustrative only.

I claim:

The ornamental design for a street sign, as shown and described.

ANNA M. ELLIOT.
